(57) **CLAIM**

The ornamental design for a cable management assembly, as shown and described.

DESCRIPTION

FIG. 1 is a lower perspective view of a cable management assembly, showing my new design.

FIG. 2 is an upper perspective view of the cable management assembly of FIG. 1.

FIG. 3 is a bottom view of the cable management assembly of FIG. 1.

FIG. 4 is a top view of the cable management assembly of FIG. 1.

FIG. 5 is a right side view of the cable management assembly of FIG. 1, and the left side view being a mirror image.

FIG. 6 is a rear view of the cable management assembly of FIG. 1.

FIG. 7 is a front view of the cable management assembly of FIG. 1.

The broken line portions of FIGS. 1-7 are included to show unclaimed subject matter only and form no part of the claimed design.

1 Claim, 4 Drawing Sheets
